ELECTRICAL SOUND REPRODUCTION

Max C. Batsel, Haddonfield, N. J., assignor to
Radio Corporation of America, a corporation of
Delaware

Application October 31, 1939, Serial No. 302,197

2 Claims. (CL 179—100.3)

This invention relates to the electrical reproduction of sound and is particularly adapted to the photoelectric reproduction of sound from film in large auditoriums, although it may be used in conjunction with other types of sound records and other locations.

The invention involves the provision of a single speaker for the reproduction of speech or similar sounds which are satisfactorily reproducible from a localized source and the provision of additional speakers over an extended area for the reproduction of music and other sound effects, the reproduction of which appears more natural from an extended source. The change from a single speaker to the multiple speakers is accomplished by means of an appropriate control track or the like synchronized with the sound record from which the sound is reproduced.

It has heretofore been customary, particularly in the reproduction of sound motion pictures, to reproduce all the sound either through a single speaker or through a group of speakers, both speech and music being treated alike. If speech is reproduced through a group of speakers and particularly if they are separated by appreciable distances, an effect equivalent to reverberation is produced and, due to the out-of-phase relation of some of the sound waves, the intelligibility of the speech is adversely affected. Speech, therefore, can be best reproduced from a single loud-speaker or from a very compact group of speakers which have the effect of a localized source. Music, on the other hand, even when produced by a solo instrument, is improved by slight reverberation, while music produced from a large group of instruments cannot be satisfactorily reproduced from a localized source, and in order to produce the proper illusion of an extended source, should be reproduced by an extended group of speakers.

In the performance of the present invention, I provide a single speaker or small group of speakers, preferably located centrally of the stage, for speech and I provide other speakers laterally spaced therefrom for the reproduction of music. The apparatus is so arranged that the additional speakers are normally silent, but when music is to be reproduced the additional speakers, together with appropriate amplifying apparatus, are turned on, giving the effect of an extended source and, if desired, producing a slightly higher volume level.

One object of the invention is to provide an improved sound reproducing system.

Another object of the invention is to provide an improved sound reproducing system which

will reproduce either speech or music to the best effect.

Another object of the invention is to provide an improved sound reproducing system which will reproduce speech from a localized source and which will reproduce music from an extended source.

Another object of the invention is to provide an improved sound reproducing system which, in cooperation with a sound record and a control record, will reproduce sounds either from a localized source or from an extended source.

Another object of the invention is to provide an improved sound reproducing system which, in cooperation with a sound record and a control record, will reproduce sounds either from a localized source or from an extended source, but in cooperation with a sound record without the control record will reproduce sounds only from a localized source.

Other and incidental objects of the invention will be apparent to those skilled in the art from a reading of the following specification and an inspection of the accompanying drawing, in which Figure 1 is a schematic diagram of my improved sound reproducing system.

Figure 2 is a schematic diagram of an alternative switching mechanism which may be used in the apparatus of Fig. 1, and

Figure 3 is an illustration of a type of sound record and control record adapted to be used in the apparatus.

Before describing my invention in detail, the type of control track adapted to be used therein will be briefly described.

A standard motion picture film is indicated at F in Fig. 3. This film carries the usual sound track S which is here illustrated as of the doubly modulated type with ground noise reduction. The control track is indicated at C and consists of an exposed portion over the sprocket hole area, which exposed portion may be of greater or less width. With film running at the standard speed of 90 feet per minute, the frequency with which the sprocket holes pass any given point is 96 per second. If the background around the sprocket holes is made dark and a beam of light passed through the sprocket holes onto an appropriate photoelectric device, a current with a frequency of 96 cycles per second will be produced. If the space between the sprocket holes is left clear, a small amount of 96 cycle current will be produced due to the opacity of the punched edges of the sprocket holes, but the quantity of this current will be small relative to that produced if the

sprocket area is blackened. If the blackened portion is varied in width or intensity, the 96 cycle output can be correspondingly varied as described in the application of Charles M. Burrill, Serial No. 181,634, filed December 24, 1937 (RCV D-5098). Likewise, if the phase relation between the sprocket holes and the exposed areas is varied, the similar control of the output may be secured as described and claimed in the application of Charles M. Burrill, Serial No. 181,635, filed December 24, 1937 (RCV D-5100), both of which are assigned to the assignee of the present application.

Referring now to the form of the apparatus shown in Fig. 1. The usual exciter lamp 10 is provided from which light is directed through an appropriate slit S1 to the sound track of the film F. The slit S1, although illustrated as a mechanical slit, for the sake of simplicity may, of course, be any other usual form such as a short focus cylindrical lens or an optical slit where a reduced image of the illustrated slit is projected on the film. The fine line of light from the slit passes through the sound track S of the film to the photocell 11. The output from the photocell 11 normally passes through the amplifier 12 to the speaker 13 which may be located, for example, in alignment with the middle of the projection screen. The amplifier 12 may be of any usual type including a sufficient number of stages of thermionic amplification to give sufficient voltage gain and power output for the purpose. The loudspeaker 13 likewise may be of any usual type.

The portion of the output from the photocell 11 may pass through the primary of the transformer 28 which is here indicated as being connected to the power supply for the photocell 11. The secondary of the transformer 28 may be connected to an amplifier 15 which, in turn, is connected to the auxiliary loudspeakers 16 and 17 which are preferably placed at each side of the speaker 13 so that, when all three speakers are in operation, sound will be produced over an extended area. The amplifier 15 may be of similar construction to the amplifier 12. The switching unit 14 is used to turn the amplifier 15 on and off or to regulate the power input thereto. In the form of the invention shown, the relay 21, which is indicated as open, may be closed by passing current through the winding 26 thereof, causing the output from the transformer 28 to be fed to the amplifier 15 and to the speakers 16 and 17.

The winding 26 is actuated as follows: A second exciter lamp 20 may be provided or light may be taken from the exciter lamp 10, and this light is directed through an aperture A upon the control track C of the film F. The aperture A may, like the slit S1, be in the form of an optical slit or the like, but a small line of light is not desirable in this case and a simple mechanical aperture may be quite satisfactory. If the aperture is too small, the signals produced by the edges of the sprocket holes at clear portions of the control track are entirely too loud and vary quite considerably, while if the aperture is fairly large, even of the same order of size as the sprocket holes themselves, these secondary signals are relatively decreased in magnitude and the signals produced by the difference in transmission of the sprocket holes and of the film are relatively accentuated.

Light passing through the aperture A and the control track is directed to a photocell 21, the

output from which is fed through a transformer 23 to the amplifier 22. The amplifier 22 need not be either of high fidelity nor of great power, as it is only necessary for it to amplify the 96 cycle impulses produced by the control track and to provide sufficient power to actuate the relay 26. The output from this amplifier 22 is fed through an appropriate rectifier 24 which is here illustrated as a thermionic rectifier, although any other equivalent type of rectifier may be substituted. The rectified current is fed through a filter composed of an inductance 25 and capacitors 26. This filter is not required to produce a high degree of filtering when a relay is used, as it is only necessary to avoid chattering of the relay. If, however, a thermionic valve is used, the filter should be sufficiently good to prevent the application of 96 cycle current to the input of the amplifier 15. The output from the rectifier filter circuit is connected, as shown, to the winding 26 of the relay 27.

It will be apparent that when the control track C is clear, the output of the photocell 21 will be at a minimum. The output of the amplifier 22 and the current fed to the relay winding 26 will therefore likewise be at a minimum and the relay contact 27 will remain open. If, however, the area between the sprocket holes on the control track C is blackened, the contrast between the black area and the open sprocket holes will cause the output of the photocell 21 to be at a maximum. In this case, the current fed by the amplifier 22 to the relay winding 26 will likewise be at a maximum, and the contact 27 will be closed, causing the speakers 16 and 17 to operate, producing sound over an extended area, as described above.

It will be apparent that if an ordinary film without any control track C is run through the apparatus, the output from the photocell 21 will remain at a minimum and the speakers 16 and 17 will remain inoperative.

An alternative switching arrangement is shown in Fig. 2. In this figure the entire switching mechanism shown in the box 14' may be bodily substituted for the switching mechanism shown at 14 in Fig. 1. In this form of the invention, an additional vacuum tube 29 is provided connected to the output of the transformer 28. This tube 29 is provided with an appropriate source of grid bias 30 which is of sufficiently high value so that if the amplifier 22 is turned off or if there is no output therefrom, the potential from the source 30 applied through the resistor 31 and the secondary of the transformer 28 will bias the tube 29 to cut-off and there will be no input to the amplifier 15. If, however, a darkened portion of the control track C is passed between the light source and the photocell 21, the output of the amplifier 22 will increase and since the rectified output from the amplifier 22 is applied across the resistor 31 in opposition to the bias supply 30, the tube 29 will become conductive and transmit an appropriate input to the amplifier 15, causing the speakers 16 and 17 to operate.

I claim as my invention:

1. In combination, means for translating sound from a record into electrical impulses, means for amplifying said impulses, localized reproducing means connected to said amplifying means for translating said impulses into sound, additional amplifying means for independently amplifying said impulses and separated reproducing means connected to said additional amplifying means for

converting said impulses into sound over an extended area, means for translating control impulses into a control current, and means actuated by said control current for causing the operation of said additional amplifying and reproducing means, whereby said additional reproducing means will function only when control impulses are provided.

2. In combination, a photoelectric sound reproducer, an amplifier connected thereto and a 10 loudspeaker connected to said amplifier, a photo-

electric control track reproducer, an amplifier and rectifier connected thereto for producing a control current, a second sound amplifier, a plurality of loudspeakers connected to said second sound amplifier, and means controlled by said control current for connecting said second sound amplifier to said photoelectric reproducer, whereby said second amplifier operates only when a control track is provided.

MAX C. BATSEL.
